UNITED STATES PATENT OFFICE

CARL H. LEIS, OF NEW CASTLE, PENNSYLVANIA, ASSIGNOR TO JOHNSON BRONZE COMPANY, OF NEW CASTLE, PENNSYLVANIA, A CORPORATION OF PENNSYLVANIA

APPARATUS FOR GRAPHITING SLEEVE BEARINGS

Application filed January 14, 1932. Serial No. 586,540.

My invention relates to apparatus for filling serrations, grooves, or other forms of receptacles in bearings with a lubricating graphite compound, relating more particularly to grooved sleeve bearings.

The invention has for its objects to provide an apparatus for filling the grooves or receptacles with the compound under high pressure and compact same therein; that will effect an even and like distribution of same to each and every groove or receptacle thereof; that will prevent any surplus compound remaining upon the bearing surface; that will be simple in operation and provide rapid and therefore economical production.

With the above objects in view, I have illustrated in the accompanying drawings a preferred embodiment of the apparatus and its application, wherein—

Figure 1 is a side elevation of the apparatus.

Figure 2 is an enlarged vertical side elevation of a portion of same, partly in section.

Figure 3 is an enlarged transverse sectional view through the apparatus, on the line III—III of Fig. 2.

Figure 4 is an enlarged elevation of a portion of the apparatus with parts, including a sleeve bearing, in section, to more clearly illustrate the method, and

Figure 5 is a transverse sectional view on the line V—V of Figure 4, of the sleeve with the compacting member disposed therein.

The apparatus comprises in structure a frame including a support 1 mounted upon legs 2, constituting a table, and a vertically disposed housing 3 mounted upon said table.

The table top has depending therefrom the rods 4 carrying a plate 5 to which is secured an air cylinder 6 provided with ports 7 and 8, respectively, and has slidably fitted therein a fluid actuated piston 9 mounted on the rod 10 extending therethrough.

Alining with the fluid cylinder and secured to the table 1 is a cylindrical member or

container 11 for confining the lubricating compound 12. The container has a piston 13 fitted therein upon the rod 10, for applying pressure to the compound and is provided at its upper end with a head or interchangeable self centering chuck 14 to engage the lower end of a sleeve 15, said chuck being open to the container and provided with an annular recess 14' as a chucking seat for the sleeve.

Directly above and alining with the container is a hollow member 16 slidably fitted for vertical movement upon the housing 3, said member having a head 17 at its lower end and adapted as a companion chuck, to engage the upper end of the sleeve 15 and close its grooves 15'.

Within the member 16 is arranged a worm wheel 18 fixed to a vertical shaft 19, said shaft having removably attached thereto a compacting member 20 adapted to move downwardly with the chuck head of the slideable member and enter the sleeve.

The compacting member is provided with one or more longitudinally disposed fluted portions 20' having their upper ends closed, said fluted portions having one edge substantially sharp and preferably on a radial line, the opposite working surface portion of the flute being preferably rounded, presenting in cross section, a substantially dual cam form as shown in Fig. 5.

The compacting member is continuously rotated in practice, being accomplished by means of a worm 21 mounted transversely within the slideable member on a shaft 22 and in engagement with the worm, the rotary movement thereof, being provided by a motor 23 mounted upon a bracket 24 secured to the housing, said motor being connected to the worm shaft by a suitable universal coupling mechanism 25 to permit the compacting member rotating regardless of the vertical movement or position of the slideable member 16.

To the upper portion of the housing is adjustably secured a slide 26, adjustment being accomplished by means of a threaded rod 27 extending through a lug 28 of the housing, and the nuts 29 and 30.

5 To the slide is secured a cylinder 31, in alignment with the member 16 and provided with ports 32 and 33, respectively, and having arranged therein a fluid actuated piston 34 the rod 35 of which is connected with the slideable member 16 at its head 36, said piston being adapted to actuate the member 16.

15 In practice, both of the cylinders 6 and 31 are to be connected, at their ports, to an air supply, and be provided with means for controlling each independently, the ports in each being employed alternately as intake and exhaust.

20 In the drawings the sleeve 15 is shown as chucked between the heads 14 and 17 ready to have the grooves 15' thereof filled with the lubricating compound, but the method of operation will be set forth as beginning 25 with the chucking of a sleeve.

Operation

Assume that the piston 34 within the upper air cylinder is in its elevated position, 30 and as such the slideable member 16 is likewise in its elevated position. Such being the case, the sleeve 15 is first seated upon the chuck head of the compound container, within the recessed portion thereof. Air being 35 supplied to the upper end of the cylinder 31 forces the piston 34 down, causing the slideable member 16 to descend. In its descent the compacting member 20 which rotates continuously enters the sleeve and the head 40 17 engages with and closes the upper end of the same, the sleeve being thus held in position. Air is admitted into the lower cylinder 6, through port 7, actuating the piston 9 therein and causing the piston 13 45 to act upon the body of lubricating compound 12 and force a charge of the compound up into the sleeve receptacles or grooves 15'. As the compound is introduced into the sleeve grooves the flutes of the compacting member 20, also become filled and being rotated, in the direction of the arrow in Fig. 4, presses or compacts the compound by a cam action, assisted by the viscosity of the compound, within the sleeve grooves, 50 completely filling said grooves and producing a uniform and smooth filling of like density in all of the grooves, flush with the bearing surface.

55 As soon as the sleeve is supplied with the compound from the container and compactor flutes, which is practically instantaneously, the air supply is cut off from the lower end of the cylinder 6, thus relieving pressure from the compound. At the same time, or immediately following same, the supply of air

to the upper end of the cylinder 31 is cut off and air supplied to the lower end thereof, by way of the port 32, thus causing the piston 34 to be actuated upwardly and elevate the slideable member 16, removing the head 17 from the end of the sleeve and at the same time withdrawing the compacting member from the interior of the sleeve, the sleeve being then removed. During filling of the grooves with the compound, sufficient leakage occurs at the top of the sleeves to expel the air therefrom.

70 75 The above description is that of one cycle of operation of the machine, the same being repeated as rapidly as the operator can supply sleeves thereto and operate the air valves.

80 While I have not shown such, it will be readily apparent that sleeve bearings with receptacles or other forms, than that shown, such as, cavities, etc. within the bearing surfaces may be filled with a compound, by means of this apparatus, as the compound will then enter the receptacles by way of the flutes in the rotary member and be compacted therein by its cam action.

85 90 While I have shown and described one embodiment of my invention, I desire that the same be regarded as illustrative only and that the appended claims be accorded the broadest construction consistent with the prior art.

95 Having shown and described such embodiment, what I claim, is—

100 105 1. An apparatus for filling grooves of a bearing sleeve with a lubricating compound comprising a container for the compound, a chuck head open to said container and adapted to be engaged by one end of the sleeve to be operated on, slidably adjustable means for closing the opposite end of the sleeve, means for forcing the compound into the grooves of the sleeve endwise thereof, and separate rotatable means for compacting the compound within the grooves.

110 115 2. An apparatus for filling grooves of a bearing sleeve with a lubricating compound comprising a container for the compound, a chuck head open to said container and adapted to be engaged by one end of the sleeve to be operated on, means for closing the opposite end of the sleeve, means for forcing the compound into the grooves of the sleeve endwise thereof, and separate compound containing means for compacting the compound within the grooves, said compacting means being rotated about the grooved surface to supply to and effect the compacting and smooth the surface of the compound.

120 125 3. An apparatus for filling the grooves of bearing sleeves with a lubricating compound comprising a container for the compound, a chuck head open to the container and adapted to be engaged by one end of a sleeve to be operated on, means adapted to be brought into engagement with the opposite end of the sleeve to close same, means for forcing

the compound into the sleeve grooves, and a rotatable member movable with said sleeve closing means and insertable within the sleeve to compact the lubricant compound 5 within the sleeve grooves while being supplied thereto, said rotatable member being provided with flutes to receive compound from the container and apply to the sleeve grooves as the member rotates to compact 10 the compound.

4. An apparatus for filling the grooves of bearing sleeves with a lubricant compound comprising a container for the compound, a chuck head having an opening therein communicating 15 with the container and provided with a self centering seat for a sleeve adapted to be engaged by one end of the sleeve to be operated on, a slidable member carrying a head to engage and close the opposite end of the sleeve, a rotatable member 20 carried by said head and insertable within the sleeve as the head descends thereon, and means for forcing the compound into the sleeve grooves, said insertable member fitting 25 the sleeve adapted to carry a supply of and compact the compound within the grooves while being forced and rotated therein.

5. In an apparatus of the class set forth, the combination of a support having a lubricating compound container thereon and provided 30 with a sleeve bearing chuck head at one end open to said container, a power actuated piston within said container, a head movable toward said chuck head to close the opposite end of a grooved sleeve bearing when placed 35 between said head and chuck head, a rotatable compound supplying compacting member movable with said head into said sleeve bearing, means for moving said head and member simultaneously, and means for 40 rotating said member, said piston adapted to force the compound into the grooves of the sleeve bearing and said rotatable member adapted to also supply and compact the compound 45 in said grooves.

6. An apparatus for filling grooves in a sleeve bearing comprising in combination, a supporting frame, a lubricating compound container carried by the frame, and provided 50 with a chuck head open, slidable means carrying a chuck head, said heads to said container adapted to chuck a grooved sleeve bearing there-between, a rotatable compacting member provided with flutes and carried 55 by said slidable means and adapted to enter the sleeve bearings, means for rotating said member, a piston within said container, and means for operating said piston to force compound through the first mentioned chuck 60 head into the sleeve grooves and compacting member flutes while said member is being rotated within the sleeve.

7. An apparatus for filling grooves in sleeve bearings with lubricating compound 65 comprising a vertically disposed frame car-

rying a lubricating compound container and upon which a sleeve bearing is adapted to be seated with the grooves communicating therewith, a slidable member including a head portion adapted to be seated upon the opposite end of the sleeve bearing, a piston mechanism for operating said slidable member, a power actuated piston within said container, a longitudinally fluted member carried by said slidable member and means carried by said slidable member for rotating said fluted member, said piston adapted to force compound into the sleeve bearing grooves and said fluted member, said member adapted by its rotary movement to also supply and compact the compound within the sleeve bearing grooves.

8. In an apparatus for filling longitudinal grooves of sleeve bearings, the combination of a container for lubricating compound having a self centering chucking recess adapted to have a sleeve bearing seated therein, a movable head adapted to seat upon the opposite end of the bearing, a longitudinally fluted member movable with said head insertable within and slidably fitting the sleeve bearing, means for forcing compound from the container into the sleeve bearing grooves and flutes of said member, and means for rotating the fluted member to compact the compound within the said sleeve bearing grooves.

9. In a machine for filling receptacles in a sleeve bearing with lubricating compound, comprising a supply container having an opening therein and provided with means for chucking the sleeve bearing about the opening upon the supply container, a rotary member adapted to enter and fit the sleeve bearing and provided with longitudinal flutes extending part way therealong and also open to the supply container, and means for forcing the compound into the receptacles by way of the flutes in the rotary member.

10. An apparatus for filling longitudinal grooves of a sleeve bearing with a bearing compound comprising in combination a vertically disposed frame having mounted thereon a like disposed container for the compound and provided with a recessed chucking head open to the container and upon which the sleeve bearing is adapted to be seated with its grooves registering with said opening, a power cylinder having a piston extending therefrom into the container, a member slidably secured to said frame and provided with a head adapted to close the opposite end of the sleeve bearing seated on the container, a fluted member carried by said slidable member and adapted to be inserted closely within the sleeve bearing as the head of the slidable member moves to close the end of the sleeve bearing, means connected with said fluted member to rotate

same, a power cylinder adjustable on said frame and provided with a piston connected to the slideable member for adjusting the slideable member relative to the container,
5 said container piston adapted to be operated from the first mentioned power cylinder to force the compound into the sleeve bearing grooves and member flutes, said fluted member adapted by its rotary movement to
10 supply and compact the compound within the sleeve bearing grooves.

In testimony whereof I affix my signature.
CARL H. LEIS.
